UNITED STATES PATENT OFFICE.

WILLIAM R. PARK, OF TAUNTON, MASSACHUSETTS, ASSIGNOR TO UNITED INJECTOR COMPANY, OF NEW YORK, N. Y., A CORPORATION OF NEW YORK.

CARBURETER.

1,167,426.

Specification of Letters Patent. Patented Jan. 11, 1916.

Application filed September 8, 1913. Serial No. 788,500.

To all whom it may concern:

Be it known that I, WILLIAM R. PARK, a citizen of the United States, and resident of Taunton, in the county of Bristol and State 5 of Massachusetts, have invented new and useful Improvements in Carbureters, of which the following is a specification.

My invention relates to carbureters for supplying combustible mixtures to internal combustion engines, and consists in improvements which while generally applicable are particularly adapted to a carbureter of the character shown and described in United States Letters Patent No. 955,353, 15 issued to me April 19, 1910. One of the chief characteristics of the carbureter described in the aforesaid patent is a gravity air valve controlling the air duct which supplies the mixing tube of the carbureter. 20 This air valve as arranged in the carbureter shown in the said patent is necessarily quite heavy, and consequently possesses considerable inertia and is therefore not quite as sensitive as might be desired.

25 I have found by investigation and demonstration that in a carbureter in which the supply of liquid fuel is graduated in some direct proportion to the supply of air it is desirable so to proportion the passages leading to the engine that a decidedly high vacuum shall be produced in the mixing tube, say one corresponding to 30 inches of water column. With such a manometric value in the mixing tube it is obvious that a valve 30 arranged as shown in my said patent will necessarily be quite heavy, and for this reason lack that sensitiveness which is desirable.

In the drawings hereto annexed which 40 illustrate my improvements,—Figure 1 is a vertical section of a carbureter; Fig. 2 is a plan view, partly broken away; Fig. 3 is a vertical section on the line 3—3 of Fig. 2; and Fig. 4 is a plan view of a detail, namely, 45 the adjusting yoke which forms part of the connections between the air valve and the fuel supply valve.

In these drawings, the carbureter casing is composed of several parts, A, A', A'', the 50 float chamber A' being formed in the lower part of the casing. The mixing tube B which is preferably in the form of a constricted passage, comprises a depending portion B' which extends down into the 55 lower part A of the casing. The fuel sup-

ply which flows through the passage C rises through the annular duct between the central air tube D and the surrounding tube N. The latter is mounted on the central boss E at the periphery of which is formed 60 the valve seat E', the latter coöperating with the air valve V. This air valve V is a gravity valve, and is provided with a seating edge at V' which seats on the periphery E' of the boss E. The diameter of this valve 65 seat is less than the external diameter of the depending portion V' of the mixing tube B, and the valve V is mounted to slide upon the exterior of this portion B' of the mixing tube. Additional bearing may, if desired, 70 be had, as at V² on the central tube N. The valve V is grooved, as at V³, this groove coöperating with the stem F which forms part of the connection between the air valve C and the needle valve I' formed by the lower 75 end of the stem I. This connection comprises also the yoke G which is split at G' and threaded to receive the threaded end F' of the rod F.

At I² the stem I is secured to the yoke G, 80 and a binding screw H serves to lock the yoke G and rod F firmly together.

A squared keyhole F² is formed in the top 85 of rod F so that by means of a suitable key, adjustment of the connection between the air valve V and fuel valve I' may be made. These connections are housed in the portion A² of the carbureter casing, this latter being supplied with a suitable cover A⁴.

Since the diameter of the lower portion 90 B' of the mixing tube B is greater than that of the seat V' of the valve V, this valve is a differential valve; therefore it may be made of light weight and consequently possess little inertia, and at the same time be 95 sufficiently heavy to control the air inlet properly under conditions of low pressure in the mixing tube B.

It is essential that the valve V shall at all 100 times slide smoothly on its bearings, and although the double bearing at V' and V² is almost certain to suffice for this purpose, I have found it advisable to apply a steadyng finger to the side of the valve V. Such a finger is shown in Fig. 3 at K, this being secured to the carbureter casing at K' and provided with a soft pad, as of felt, at L, which bears with a light touch against the valve V. This steadyng finger being 105 opposite to the connection with the fuel valve 110

serves effectually to check any tendency of sticking or chattering of the valve.

I claim:

1. In a carbureter, the combination of a tubular gravity air valve, a seat therefor co-acting with the lower end of the tubular valve, a mixing tube entering the upper end of the tubular air valve and constituting a sliding bearing for the valve, the diameter of the upper end of the tubular bore of the air valve being greater than that of the lower end, a fuel inlet communicating with the interior of the mixing tube, and a needle valve to control the fuel supply, connected with and operated by the gravity air valve.
2. In a carbureter, the combination of a tubular gravity air valve, a seat therefor co-acting with the lower end of the tubular valve, a mixing tube entering the upper end of the tubular air valve and constituting a sliding bearing for the valve, the diameter of the upper end of the tubular bore of the air valve being greater than that of the lower end, a fuel inlet communicating with the interior of the mixing tube, and a needle valve to control the fuel supply, connected with and operated by the gravity air valve.

lower end, a steadyng finger bearing on the gravity air valve, and a fuel inlet communicating with the interior of the mixing tube.

3. In a carbureter, the combination of a tubular gravity air valve, a seat therefor co-acting with the lower end of the tubular valve, a mixing tube entering the upper end of the tubular air valve and constituting a sliding bearing for the valve, the diameter of the upper end of the tubular bore of the air valve being greater than that of the lower end, a fuel inlet communicating with the interior of the mixing tube, a needle valve to control the fuel supply, connected with and operated by the gravity air valve, and a steadyng finger bearing on the gravity air valve.

Signed by me at Boston, Massachusetts, this 4th day of September 1913.

WILLIAM R. PARK.
